UNITED STATES PATENT OFFICE.

HENRY B. RAYNES, OF BUFFALO, WEST VIRGINIA.

RAILROAD-CROSSING SIGNAL.

Application filed March 10, 1924. Serial No. 698,164.

To all whom it may concern:

Be it known that I, HENRY B. RAYNES, a citizen of the United States, residing at Buffalo, in the county of Putnam and State 5 of West Virginia, have invented certain new and useful Improvements in Railroad-Crossing Signals, of which the following is a specification.

This invention relates to railway signals 10 and has special reference to crossing signals employing a flickering light for night signaling and an oscillating semaphore blade for day signaling.

One important object of the invention is 15 to improve the general construction of devices of this character.

A second important object of the invention is to provide improved rail supporting means for actuating the signal upon the 20 passage of trains.

A third important object of the invention 25 is the provision of means specially adapted for actuating the signal upon the approach of a train on a single track in either direction.

With the above and other objects in view 30 as will be hereinafter apparent, the invention consists in general of certain novel details of construction and combination of parts hereinafter fully described, illustrated 35 in the accompanying drawings and specifically claimed.

In the accompanying drawings like characters of reference indicate like parts in 35 the several views, and:

Figure 1 is a side elevation partly broken away showing the signal and its actuating means in relation to a track rail.

Figure 2 is a detail perspective view of a 40 certain rock shaft used in connection herewith.

Figure 3 is a detail section to an enlarged scale on the line 3—3 of Figure 1.

Figure 4 is a similar section on the line 45 4—4 of Figure 1.

Figure 5 is a detail view looking at one side of the semaphore from the direction of the arrows on the line 5—5 of Figure 1.

Figure 6 is a detail section showing the 50 means for holding the rock shaft in position to keep the semaphore blade vertical.

In the embodiment of the device here shown there is disclosed a track rail 10 and a semaphore having a hollow stand 11 and 55 provided at its upper end with a shaft 12 whereon is fixed a pair of semaphore blades

13 and 14, the former being longer than the latter. Supported between these blades on a lamp stand 15 is a lamp 16. Projecting from the bottom portion of the longer 60 blade is a rock arm 17 which is connected by a link 18 with a rock arm 19 connected to a sleeve 20 fixed upon a rock shaft 21 supported in suitable bearings, not shown, in the bottom of the stand 11. On the rock 65 shaft 21 is also mounted a sleeve 22 from which project pairs of arms 23, rollers 24 being revolvably mounted between said arms. Within the hollow stand 11 are lugs 25 which support rollers 26 and springs 27 70 of the coil variety having their ends engaged on the respective rollers 24 and 26 as shown in Figures 2 and 6, these springs acting to hold the arms 23 normally horizontal and thus also holding the rock arms 75 19 in horizontal position.

At the inner or track end of the rock 80 shaft 21 there is provided a double rock arm 28 which normally rests in vertical position and has at its upper and lower ends laterally projecting pins 29. On these pins are mounted the slotted ends 30 or links 31 which pass through guard tubes or pipes 32 85 fixed to the inside of the rail 10 by brackets or clips 33. Between certain pairs of these brackets the tube or pipe 32 is enlarged as at 34 and these enlarged portions contain pairs of opposed compression springs 35, said springs bearing at their adjacent ends on a collar 36 on the link or rod 31. Between other pairs of brackets 33 the rail is 90 cut away as at 37 and pivoted to a block 38 below this cut away portion is a rock arm 39 carrying at its upper end a roller 40 located in the gap formed by the cut away 95 of the rail. This arm 39 is guided by a guide bar 41 and the rods or links 31 are connected to a strip 42 surrounding the respective arm 39. It is to be observed that 100 there may be a number of these rollers 40 and, as shown in Figure 1, the track arrangement extends in both directions from the semaphore stand. In operation a train approaching from the right of Figure 1 will engage, with its wheels, the rollers 40 and this will cause the arms 39 to rock to the left and thus, through the rod or link 31, actuate the rock shaft 21 and thereby oscillate the 105 semaphore blade 13. At night when the lamp is lighted this oscillation will alternately cover and uncover the lamp thus causing a flickering thereof. It will be

noted that, by the peculiar arrangement of the slot end 30 the track apparatus on one side will operate without moving the apparatus of the other side and that, after a 5 train passes the semaphore actuating the track apparatus beyond the semaphore will not operate the latter.

There has thus been provided a simple and efficient device of the kind described 10 and for the purpose specified.

It is obvious that minor changes may be made in the form and construction of the invention without departing from the material spirit thereof. It is not, therefore, 15 desired to confine the invention to the exact form herein shown and described, but it is desired to include all such as properly come within the scope claimed.

Having thus described the invention, 20 what is claimed as new, is:

1. The combination with a semaphore stand and its blade; of railroad track, and track supported means for repeatedly oscillating said blade including a rock shaft having operative connection to said blade and having a rock arm at one end, a rod having a pin and slot connection to said rock arm and supported adjacent a track rail, and a plurality of levers each pivotally connected 25 to said rail and projecting thereabove for engagement by the wheels of a train, said levers each being connected intermediate its ends to the rod.

2. The combination with a semaphore stand and its blade; of railroad track, and track supported means for repeatedly oscillating said blade including a rock shaft having operative connection to said blade and having a rock arm at one end, a rod having a pin and slot connection to said rock arm and supported adjacent a track rail, a plurality of levers each pivotally connected to 30 said rail and projecting thereabove for engagement by the wheels of a train, said levers each being connected intermediate its ends to the rod.

3. The combination with a semaphore stand and its blade; of railroad track, and track supported means for repeatedly oscillating said blade including a rock shaft having operative connection to said blade and having a rock arm at one end, a rod having a pin and slot connection to said rock arm and supported adjacent a track rail, a plurality of levers each pivotally connected to 35 said rail and projecting thereabove for engagement by the wheels of a train, said levers each being connected intermediate its ends to the rod.

ends to the rod, and spring means normally holding said rod in position to elevate the wheel engaged ends of the levers.

3. The combination with a semaphore stand and its blade; of railroad track, and track supported means for repeatedly oscillating said blade including a rock shaft having operative connection to said blade and having a rock arm at one end, a rod having a pin and slot connection to said rock arm and supported adjacent a track rail, a plurality of levers each pivotally connected to said rail and projecting thereabove for engagement by the wheels of a train, said levers each being connected intermediate its ends to the rod, spring means normally holding said rod in position to elevate the wheel engaged ends of the levers, and other spring means normally holding the semaphore blade in vertical position. 65

4. In combination, a track rail, a semaphore stand adjacent said rail, a shaft in the upper part of said stand extending transversely thereof, a blade fixed on said shaft, spring means normally holding said blade raised in vertical position, a rock shaft extending between the rail and stand, corresponding rock arms on said shafts, a link connecting said rock arms, a double rock arm on the end of the shaft adjacent the rail pins projecting from said double rock arm adjacent its ends, rods supported from said rail and extending in opposite directions from the rock shaft, slotted ends on said rods engaging said pins, levers for each rod each having its lower end pivotally connected with the rail and having its upper end provided with a roller projecting above the rail head said levers each being connected intermediate its ends to a respective rod, and spring means normally holding said levers in vertical position. 75 80 85

In testimony whereof I affix my signature.

HENRY B. RAYNES.
